COMBINED BATTERY POWERED SURGICAL DRILL AND BATTERY CANISTER THEREFOR

Meyer Fishbein, 12020 Saltair Place,
Los Angeles, Calif. 90049

Filed Feb. 19, 1974, Ser. No. 443,361

Term of patent 7 years

Int. Cl. D24—02

U.S. Cl. D83—12 R

Fig. 1

Fig. 2

Fig. 3

Fig. 7

FIG. 1 is a side elevation of a combined battery powered surgical drill and battery canister therefor, showing my new design;

FIG. 2 is a front elevation thereof;

FIG. 3 is a top plan view thereof;

FIG. 4 is an elevation as seen from the side opposite of FIG. 1;

FIG. 5 is a rear elevation thereof;

FIG. 6 is a bottom elevation thereof; and

FIG. 7 is a fragmentary front perspective of a modified embodiment of the surgical drill illustrated in FIG. 1.

I claim:

The ornamental design for a combined battery powered surgical drill and battery canister therefor, substantially as shown and described.
